UNITED STATES PATENT OFFICE.

JOSEPH J. JACKMAN, OF DANVERS, MASSACHUSETTS, ASSIGNOR OF ONE-FOURTH TO
FRANCIS H. CASKIN, OF DANVERS, MASSACHUSETTS.

GRID FOR THERMIONIC TUBES.

Application filed April 27, 1925. Serial No. 26,199.

This invention deals with the provision of an improved grid for use in three-element thermionic valves. Valves of this character consist in an enclosing member such as a glass bulb capable of high evacuation and three diverse electrical elements suitably spaced one from the other within the bulb or tube as the same is commonly known. The efficiency of such an arrangement depends in a large degree upon the structural stability of the several elements and their ability to stand vibration and shock. It is also evident that the effect of the so called grid in operating as a valve for the electronic stream is dependent upon its position with respect to the filament and to the plate.

As contemplated, a plate and a filament, both of conventional type are separated by a grid capable of operating as a valve with great efficiency. As it is customary to give to the filament the form of an inverted letter V, this invention develops a grid which shall conform to the shape of the filament and produce the maximum result in affecting the electronic stream.

Specifically it is an object of this invention to produce a suitable grid capable of withstanding hard usage and severe vibration.

A further object of the invention is to give to the grid a configuration which follows generally that of the contained filament.

It is also a further object of this invention to form the grid from a single piece of sheet metal in such a way that a rigid structure is obtained complying in great degree with the requirements in all such devices.

It will also be apparent that this invention simplifies the construction and assemblage of these devices and produces an article economically and capable of efficient operation over a long time.

Further advantages will be evident from the following description of one preferred form of my invention, in which,

Fig. 1 is a vertical section on the line 1-1 of Fig. 2,

Fig. 2 is a plan view of the device,

Fig. 3 is a sheet metal blank used and

Fig. 4 shows the grid as formed from the blank.

By way of example, I have shown a glass stem or support 5, of conventional tubular form the upper portion of which is brought

together as shown at 6 to form a hermetic seal through which the various conducting wires are carried. The outer conducting posts 7, 7, form supports for the opposite plates 8, 8, which provide a vertical recess as shown in Fig. 2. One supporting member 7 projects through the stem 5 and is continued as the conductor 9.

A central post 10 is offset around one plate 8 and projects vertically above the latter in order to form a support for a horizontal wire 11 the end of which terminates within the recess formed by the plates 8 and centrally of the stem 5.

On opposite sides of the upright 10, the stem member 6 carries lead wires 12, 12. These lead wires terminate in divergent ends beneath the level of the plates 8 and as indicated clearly in Fig. 1. A heating filament 13 is carried upward from one wire 12 around the end of wire 11 and back to the other wire 12. The wires 12 are connected with the leads 14 of the heating circuit.

Vertically disposed in the upper member 6 and between each pair of members 7 and 12 is an upright rod 15.

The details above described are those of the conventionally formed thermionic valves and in the usual type of such devices the members 15, 15 extend to the top of the plates 8 and form supports upon which a fine wire is coiled to be operated as a valve or grid by current oscillations received through a lead 16 connected to one of the posts 15.

It will be observed that the filament 13 has the form of an inverted letter V. The grid member 17 is made of sheet metal from a blank of the trapezoidal form shown in Fig. 3. It will be observed that the side edges of this blank are substantially parallel to the side members of the filament 13. The metal of the member 17 is of sufficient thickness to be self-supporting when mounted upon the members 15, 15 and thus permit them to end near the base of the sheet metal grid. The blank for this grid is transversely slotted as shown in Figs. 1 and 4 and the resulting strips or ribbons are bent outward in opposite directions as indicated in 18, 19 to produce a substantially hexangular grid as is shown in Fig. 2.

It will be apparent that the ribbons or strips 18, 19 are of increasing length from top to bottom of the grid member 17 in or-

der that all points may be of substantially constant distance from the filament wire 13.

The operation of a thermionic valve of this type is already well known and it will be evident that the grid above described possesses many advantages not found in the conventional form. In the first place being of sheet metal it will be sufficiently rigid to be self-supporting and not to require the members 15 to be carried up the full length of the sides of the grid. Due to the tapering form of the grid the resulting recess conforms closely to the filament and the latter is thus uniformly spaced from the valve member or grid throughout the length of the filament. The disposition of alternate strips or ribbons 18, 19 on opposite sides of the filament establishes a path for the current oscillations from conductor 16 in such manner as to surround the filament in a uniform manner and with a very short air gap.

It will be apparent that this structure contributes to the economy and simplicity of manufacture and produces an article capable of long and efficient service under most adverse conditions.

While one preferred form of my invention has been illustrated it will be apparent that numerous minor changes in detail can be carried out within the scope of the invention as defined in the appended claims.

What I claim is:

1. A grid for thermionic tubes consisting of a flat sheet of metal the medial portion of which is transversely slotted for progressively increasing distances throughout its length and the resultant strips bent outwardly to produce a longitudinal tapering passageway in the plane of said sheet metal.

2. A grid for thermionic tubes consisting of a flat sheet of metal the medial portion of which is transversely slotted for progres-

sively increasing distances throughout its length and the resultant strips alternately bent outwardly in opposite directions.

3. A grid for thermionic tubes consisting of a trapezoid of sheet metal having its medial portion slotted parallel to its base for varying distances and the resultant strips bent outwardly to form a tapering longitudinal passageway.

4. In a thermionic tube the combination with an inverted V-shaped heating filament, of a grid formed of sheet metal having parallel integral portions of progressively varying lengths alternately disposed on opposite sides of the plane of the filament and terminating at a uniform distance therefrom.

5. In a thermionic tube the combination with an inverted V-shaped heating filament, of a grid formed of sheet metal having parallel integral portions of progressively varying lengths alternately disposed on opposite sides of the plane of the filament and terminating at a uniform distance from the filament and in the plane thereof.

6. In combination, a heating filament and a sheet metal grid having parallel integral portions alternately disposed on opposite sides of the filament said parallel portions extending in the direction of their length a uniform distance beyond the filament.

7. A sheet metal control electrode for an electron discharge device, comprising a plurality of sets of members bent from a planary punched sheet to provide an enclosing structure of members connected by side supports, said members being of progressively increasing lengths to provide an enclosure of flattened truncated cone shape.

In testimony whereof I have affixed my signature.

JOSEPH J. JACKMAN.
